UNITED STATES PATENT OFFICE.

BRUNO HOLZHÜTER, OF HEIDELBERG, GERMANY.

NAILING MACHINE FOR SHOES.

Application filed January 22, 1926, Serial No. 83,037, and in Germany April 30, 1925.

This invention relates to a shoe-nailing machine in which the nailing is done in oblique direction simultaneously in two rows, the nails in the one row being displaced with 5 regard to the nails in the other row. By this kind of nailing a much greater durability of the nailed sole is obtained than formerly and by the nailing in two rows simultaneously the efficiency of the machine is 10 considerably increased.

An embodiment of the invention is shown, by way of example, in the accompanying drawing in which—

Fig. 1 shows the machine in side elevation 15 and

Fig. 2 is a front end view.

In the frame-like casing *a* a shaft *b* is horizontally journalled in ball bearings. On one end of shaft *b* two belt pulleys *c*, *d* are keyed. 20 The belt pulley *d* is constructed to form a clutch element on its inner surface, the other clutch element *f* shiftably mounted on shaft *b* being pressed by the action of a spring *g* into engagement with the clutch element *d*. 25 A grooved disk *h* having a cam *i* on its inner surface is arranged inside the frame *a*. The cam *i* is designed to act upon a roller *k* fixed on a lever *l*. The outer end of lever *l*, projecting from the frame *a*, is hingedly connected with a clutch lever *m*.

By the rotation of a grooved disk *h* a rack *n*, movably mounted in the upper portion of frame *a* is shifted to and fro through the intermediary of a roller *o*, so that 35 toothed wheels *p* are rotated which raise and lower tool holders *r*. In the head of the machine four tool holders *r* are arranged, two for holding the pricking tools and two for holding the inserting tools. At every 40 working phase the corresponding pair of tool holders is in engagement with the toothed wheels *p* and *q*, the other pair of

tool holders being shifted in lateral direction by the rotating eccentric *t* engaging with the guides of the tool holders, so that the toothed 45 wheel cannot gear with the shifted tool holders.

The eccentric *u* acts upon a lever which operates the knife *w* which severs the pegs fed the knife in the shape of a strip, the cut 50 off pegs being held in the position to be driven in. The shoe on a last or horn arranged underneath the nail head is moved at the pegging or nailing by a catch *z* arranged on a lever 1 oscillatably mounted on 55 a bolt 2 having a spherical head and moved in lateral direction by an eccentric 3 and in vertical direction by an eccentric 4.

A rod 5 hingedly fixed to the lever *l* is 60 operated by means of a pedal (not shown) and shifts the clutch element *f* when the pedal is being depressed so that the clutch coupling is disengaged. When the pedal is further depressed the clutch element *f* is 65 pressed on a ring 6 whereby the machine is stopped.

I claim:—

A shoe nailing machine comprising in combination, a head, a pair of tool holders obliquely mounted in said head and carrying 70 tools for piercing holes in the work operated upon, a second pair of tools obliquely mounted in said head and carrying tools for inserting pegs in the holes so formed, a main driving shaft, a horizontal rack, a grooved 75 disk on said shaft, a roll carried by said rack engaging the groove in said disk, gear wheels operated from said rack, and means for alternately bringing said pairs of tool holders into operative engagement with said 80 gear wheels.

In testimony whereof I affix my signature.

BRUNO HOLZHÜTER.
